(57) **CLAIM**

The ornamental design for single-dose dissolvable personal care unit, as shown and described.

DESCRIPTION

FIG. 1 is a perspective view of a first embodiment of single-dose dissolvable personal care unit embodying our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

Any patent application or patent to which this application claims priority or benefit thereof, is hereby incorporated herein by reference in its entirety.
